UNITED STATES PATENT OFFICE.

CHARLES M. BURGESS, OF NEW BRITAIN, CONNECTICUT, ASSIGNOR TO THE RUSSELL & ERWIN MANUFACTURING COMPANY, OF SAME PLACE.

DESIGN FOR A DOOR-CHECK FRAME.

SPECIFICATION forming part of Design No. 30,692, dated May 2, 1899.

Application filed March 28, 1899. Serial No. 710,835. Term of patent 14 years.

To all whom it may concern:

Be it known that I, CHARLES M. BURGESS, a citizen of the United States, residing in New Britain, in the county of Hartford and State of Connecticut, have invented and produced a new and original Design for a Door-Check Frame, of which the following is a specification, reference being had to the accompanying drawings, in which—

10 Figure 1 is a plan view of a door-check frame, showing my new design. Fig. 2 is a sectional view of the same on the line $x-x$ of Fig. 1.

As shown in the drawings, the top A is of 15 a square contour with two corners thereof rounded, as at 3. On this side there is a border-ledge B of a rounded form on its outer side 4, while its inner side or face 5 is straight and at right angles to the top A. There is a 20 central circular opening 6 in the top and a beveled countersunk hole 7 at each corner. The

edges 12 of the top are at right angles to the top of the face thereof. The body C of the frame extends downwardly from the top from around the opening 6 and is of a cylindrical form exteriorly. The interior 10 of the body C is cylindrical from its lower end upwardly to near the top, where it extends inwardly on a curve, as at 11, to meet the opening 6, all as shown. At its lower end the body 30 has several projections 8 by the sides of rectangular recesses 9.

Having described my invention, what I claim as new, and desire to secure by Letters Patent, is—

35 The design for a door-check frame, as herein shown and described.

CHARLES M. BURGESS.
